INVENTOR

PER Albert J. Fiske
ATTORNEY

UNITED STATES PATENT OFFICE.

ALBERT L. ARENBERG, OF CHICAGO, ILLINOIS.

DESIGN FOR A SHADOWLESS LAMP.

Application filed March 11, 1929. Serial No. 30,430. Term of patent 7 years.

To all whom it may concern:

Be it known that I, ALBERT L. ARENBERG, a citizen of the United States, residing at Chicago, in the county of Cook and State of Illinois, have invented a new, original, and ornamental Design for a Shadowless Lamp, of which the following is a specification, reference being had to the accompanying drawing, forming part thereof.

The figure is a vertical elevation of the shadowless lamp, showing my new design.

I claim:

The ornamental design for a shadowless lamp as shown.

In testimony whereof I affix my signature.

ALBERT L. ARENBERG.
